GUNRACK

William G. Levy, North Conway, N. H.

Application October 3, 1951, Serial No. 249,550

3 Claims. (Cl. 211—4)

1

This invention relates to gun racks. More particularly it is concerned with a new and improved rack for holding one or more guns in the sportsman's home, simple and inexpensive to construct, and embodying a novel locking arrangement to prevent unauthorized removal of any of the guns.

So far as I am aware, there is no satisfactory and inexpensive locking type of gun rack now on the market for use in the home. Yet there is a great need for such equipment, enabling the sportsman to keep his firearms under lock and key and yet readily available for use.

It is a primary object of my invention to provide such a simple and inexpensive gun rack, which will nevertheless assure that the weapons will be securely locked and available only to authorized persons.

Another object of the invention is to provide a gun rack of the type described, which will be attractive in appearance, adaptable to hold the various sizes and shapes of rifles and shotguns, and including a storage compartment for ammunition and revolvers or pistols.

The invention consists of the novel arrangement and combination of parts, as more particularly described in the following detailed description of a preferred embodiment thereof, taken together with the accompanying drawings, in which like numerals refer to like parts in the several views, and in which,

Fig. 1 is a front elevation of a gun rack embodying the invention;

Fig. 2 is a fragmentary detail view, showing the cooperative relation of the bolt and locking bar;

Fig. 3 is another fragmentary detail, showing the socket and slot in the lower portion of the upright in which the locking bar and bolt are mounted; and

Fig. 4 is another fragmentary detail, showing the special configuration of the vertical aperture in the upper portion of the upright so as to removably receive the upper end of the locking bar.

The structure consists generally of a horizontal baseboard 10, to the opposite ends of which are attached a pair of vertical uprights 12 and 14. The uprights are held together at their top ends by a transverse shelf 16. Optionally a lower shelf 18 may be set a short distance above the board 10 to strengthen the base portion of the rack to provide space for mounting a drawer 20, having a lock 22, for containing ammunition, revolvers, gun cleaning supplies, etc. The rack also may optionally be provided with a rear panel 24. The right hand upright 14 (as seen in Fig. 1)

is provided with a series of generally horizontal transverse openings 26, adapted to receive various sized barrels of rifles or shotguns, the latter being indicated by dash and dot lines. In the left hand upright 12 opposite the openings 26, there are formed frontwardly opening slots 28 to receive the small-of-the-stock of the usual sized rifle or shotgun. Each slot 28 is inclined somewhat downwardly to the left to conform with the slope of the portion of the gun it is designed to hold. The base of the upright 12 has a forwardly offset portion 30 having an upwardly facing socket 32, into which may be inserted the locking bar 34. Similarly the upper portion of the upright 12 has an overhang 36, directly above the projecting portion 30, the overhang being provided with a generally vertical aperture 38 for the upper end of the locking bar 34. From a consideration of Figs. 3 and 4 it will be observed that the bar 34 may be readily removed from the gun rack, assuming it to be unlocked, by raising it upwardly in the slot 38 so that its lower end is free of the socket 32. The lower end may then be pulled outwardly from the rack, and then downwardly, so as to remove the bar entirely from the aperture 38. The aperture 38 is sloped downwardly and forwardly, as shown in Fig. 4, to permit the tilting of the bar 34 during insertion and withdrawal of the same.

The novel locking arrangement, according to the invention, will be apparent from a study of Figs. 2, 3 and 4. The forwardly offset base portion 30 of the upright 12 is provided with a horizontal rearwardly extending bore 40, which intersects the socket 32. The bore 40 is provided with a lateral slotted opening 42, which opens into the space between the shelves 10 and 18, adjacent one side of the drawer 20. The bore 40 is adapted to receive a bolt 44, which may be manually reciprocated into and out of a locking recess 46 in the lower portion of the bar 34. In order to facilitate manipulation thereof, the bolt 44 is provided with a handle 48 which extends through the slot 42 and may be easily reached by removing the drawer 20 and reaching into the space between the panels 10 and 18. In order to assure that the bolt 44 will not become accidentally dislodged from its socket 46, the forward end of the slot 42 is scooped out to provide a locking shoulder 50, behind which the handle 48 may seat. Thus when the bolt 44 is in locked position the handle 48 is rotated downwardly, as shown in dotted lines in Fig. 2, behind the shoulder 50, which firmly secures the bar locking mechanism against accidental displacement.

The motion of the bolt 44 during locking and unlocking is indicated by arrows in Fig. 2.

In use, the gun rack may first be laden with any convenient number of rifles or shotguns, the barrels first being inserted through the openings 26 and the small-of-the-stock of each weapon then placed in one of the slots 23. Next the locking bar 34 is inserted upwardly in the aperture 38 and its lower end dropped down into the socket 32. With the drawer 20 removed, the handle 48 is pulled forwardly to seat the bolt 44 in its recess 45 in the lower end of the locking bar 34. The outer end of the handle 48 is then manually rotated to a position behind the shoulder 50, completing the locking operation. The drawer 20 is next inserted and the lock 22 operated with a key. It is evident that the casual observer will be unable to detect the exact locking arrangement employed. And even if the drawer 20 should accidentally be left unlocked, it is unlikely that small children would be able to discover how to disengage the bar 34 so as to remove the weapons.

I have found that the various parts of my new and improved gun rack may be readily fabricated of wood, including the bar 34, bolt 44 and handle 48, the holes and sockets being readily prepared by means of a mortising machine. It is evident, however, that, if desired, the construction may be made more rugged and various of the parts be made of steel or other metal, so as to make exceedingly difficult removal of any of the guns without first removing the drawer 20. Likewise it is evident that the aperture 38 need not extend completely through the overhang 36, but may be merely a socket of sufficient depth to permit raising of the locking bar 34 out of its lower socket 32.

In order to accommodate different sizes and styles of guns, I may optionally provide slots 23 of a variety of different widths in the same rack. Likewise, it is evident that the rack may be built to accommodate, within reason, any number of rifles or shotguns, either one or two weapons or more. Likewise, optionally, I may extend the handle 48 to a position behind the drawer 20, where it may be suitably connected to the lock 22 so as to be operated by a key instead of manually.

While I have herein disclosed a presently preferred embodiment of the invention, it is evident that the same is susceptible of various other changes and modifications by those skilled in the art and nevertheless within the spirit and scope of the appended claims.

I claim:

1. A gun rack comprising a base, a pair of spaced uprights extending from either side of said base, one of said uprights having at least one opening facing the other upright and adapted to receive the barrel of a gun, said other upright having at least one forwardly opening slot op-

posite said opening and shaped to receive the small-of-the-stock of said gun, said other upright also having a forwardly over-hanging portion above and a forwardly extending portion below said slot, said overhanging portion having an aperture opening downwardly and said extending portion having a socket facing upwardly, a locking bar received in said aperture and socket and closing the front of said slot for locking the stock of said gun therein, said locking bar having a recess near its lower end at a point located within said extending portion when said bar is in its locked position, and a bolt movably mounted in said extending portion engaging said recess and locking said bar against upward movement when in one position, and releasing the same when in another position.

2. Apparatus in accordance with claim 1 including a drawer mounted on said base between said uprights and an operating handle connected to said bolt, said handle being concealed by said drawer when the latter is in place.

3. A gun rack comprising a base, a pair of spaced uprights extending from either side of said base, one of said uprights having at least one opening facing the other upright and adapted to receive the barrel of a gun, said other upright having at least one forwardly opening slot opposite said opening adapted to receive another part of said gun, said other upright also having a forwardly overhanging portion above and a forwardly extending portion below said slot, said overhanging portion having an aperture opening downwardly and said extending portion having a socket facing upwardly, a locking bar received in said aperture and socket and closing the front of said slot for locking said part of said gun therein, said locking bar having a locking portion at its end located within said extending portion when said bar is in locked position, and a lock operating within said extending portion and cooperating with said locking portion of said bar, said lock being movable for locking said bar in said aperture and socket when in one position and permitting removal of said bar therefrom when in another position.
